(57) **CLAIM**

The ornamental design for a multi-combined tossing ball, as shown.

DESCRIPTION

FIG. 1 is a perspective view of a multi-combined tossing ball showing my new design;

FIG. 2 is a right side elevational view thereof; the left elevational view being a mirror image;

FIG. 3 is a top plan view rotated 90 degrees thereof; the bottom plan view is a mirror image; and,

FIG. 4 is a front elevational view thereof; the back side view being a mirror image;

FIG. 5 is a side elevational view of a second embodiment of FIG. 1;

FIG. 6 is a side elevational view of a third embodiment of FIG. 1;

FIG. 7 is a side elevational view of a forth embodiment of FIG. 1; and,

FIG. 8 is a side elevational view of a fifth embodiment of FIG. 1.

It being understood that the alternate embodiment views not shown are the same form as seen in FIGS. 1 through 4 except for the multi-combined tossing ball surface.
